(57) **CLAIM**

The ornamental design for an intelligent toilet seat cover, as shown and described.

DESCRIPTION

FIG. 1 is a perspective view of an intelligent toilet seat cover showing our new design;

FIG. 2 a perspective view viewed from another angle thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines depict portions of the intelligent toilet seat cover in which the design is embodied that form no part of the claimed design.
